(57) **CLAIM**

The ornamental design for a towel bar, as shown and described.

DESCRIPTION

FIG. 1 is a front elevational view of a towel bar showing my new design;

FIG. 2 is a top plan view thereof;

FIG. 3 is a left side view thereof, the opposite side being a mirror image of the side shown; and,

FIG. 4 is a rear elevational view thereof.

The horizontal bar element is shown broken-away in the views to indicate indeterminate length.
